ATTORNEY

UNITED STATES PATENT OFFICE.

ANDREW REED ROWE, OF MIDLAND, PENNSYLVANIA.

APPARATUS FOR CASTING METAL PRODUCTS.

Application filed January 12, 1927. Serial No. 160,732.

This invention relates to an apparatus for casting metal products and is an improvement in the apparatus described in my patent of December 13, 1921, No. 1,399,798.

- 5 An object of the invention is to construct a hot top easily insertible in the top of a mold, but which will always allow the escape of the gases from the mold as the metal is poured into the mold.
- 10 Another object of the invention is to provide for ready removal of the bottom of the hot top for repairs or replacement.

Another object of the invention is to so design the parts that the hot top may be 15 of a shape easily molded and therefore inexpensive to construct.

With these and other objects in view, which will be developed as the description proceeds, I will now describe my invention in 20 connection with the accompanying drawings in which:

Figure 1 is a sectional view on the line 1—1 of Fig. 2.

Fig. 2 is a top plan view of the mold and 25 hot top.

Fig. 3 is a section of a modification taken on the line 3—3 of Fig. 4.

Fig. 4 is a top plan view of the device shown in Fig. 3.

30 In the modification shown in Fig. 1, 1 is the hot top having lugs 2—2 and 3—3 to support it in the top of the mold 4. This hot top 1 is preferably made of refractory material and molded with the lugs thereon so the hot top may be set in the end of the 35 mold as shown in Fig. 1 and is supported in position on the ends of the lugs.

The bottom 5 as shown in Figure 1 may be 40 constructed with the inclined sides so as to fit on the tops of inclined portions 6 of a ledge 7 projecting inwardly around the interior of the hot top. The bottom 5 has holes 45 8—8 to break up the stream of metal as it is poured into the hot top from above and allow the metal to run down through the holes 8—8 to break up the large stream as it issues from the ordinary ladle (not shown). In the modification shown in Figure 1, there 50 is a skirt 10 extending downwardly from the bottom 5 to prevent the spattering of the metal as it passes through the holes 8 against the inner sides of the hot top.

As the metal runs into the mold 4, quantities 55 of gas are released and the hot top fits loosely in the top of the mold so that the gas can escape around the bottom of the hot top be-

tween the lower portion thereof and the interior of the upper portion of the mold between the lugs 2—2 and 3—3 as indicated by the drawings.

60 In the modification shown in Fig. 3 the hot top 1' has an interior ledge 7' and the bottom of the hot top 5' having the holes 8' rests on the ledges 7'. In this case I have lugs 2'—2', 3'—3' near the middle of the 65 sides of the hot top. This allows plenty of open space between the bottom of the hot top and the mold 4' for the escape of the gases.

70 In either modification the body of the hot top is in a shape to be conveniently molded of refractory material. In placing the same in the top of a mold it may be easily grasped by the lugs and placed in position and since it is supported in the mold by the lower end 75 of the lugs there is always enough space between the bottom of the hot top and the interior of the mold for the escape of gases. The bottoms which are also molded from refractory material are easily removed and 80 cleaned, or new bottoms substituted. Other manufacturing advantages are apparent from my construction and the hot top has been found to be easily handled and efficient in its action.

85 I claim as my invention:

1. A hot top of refractory material comprising a body portion, a ledge integrally included around the interior of the body portion, a separate bottom with holes therein 90 adapted to rest on said ledge and having a portion extending below said ledge, integral lugs molded on the exterior of the body portion, the bottoms of which are above the bottom of the body portion, the bottom of the 95 body portion being smaller than the interior of the mold to allow escape of gases from the mold when the hot top is full of molten metal.

2. A hot top comprising a body portion, a 100 ledge on the interior of the body portion, said ledge having an inclined upper surface and a separable bottom for the hot top with an inclined portion to rest on and fit the inclined upper surface of the ledge, said bottom having holes therethrough, and a skirt extending from its lower side below the ledge in the hot top to prevent spattering of the metal against the inner sides of the hot top as the metal passes through said holes.

105 In testimony whereof I affix my signature.
ANDREW REED ROWE.
